C. J. ERICKSON

AUTOMATIC TELEPHONE SYSTEM

Filed Sept. 7, 1920

Inventor
Charles J. Erickson.
Chas. T. Candy
H. H. C.

UNITED STATES PATENT OFFICE.

CHARLES J. ERICKSON, OF CHICAGO, ILLINOIS, ASSIGNEE TO AUTOMATIC ELECTRIC COMPANY, OF CHICAGO, ILLINOIS, A CORPORATION OF ILLINOIS.

AUTOMATIC TELEPHONE SYSTEM.

Application filed September 7, 1920. Serial No. 408,541.

To all whom it may concern:

Be it known that I, CHARLES J. ERICKSON, a citizen of the United States of America, and resident of Chicago, in the county of Cook and State of Illinois, have invented certain new and useful Improvements in Automatic Telephone Systems, of which the following is a clear, concise, and exact description.

10 My invention relates in general to an automatic telephone system and more particularly to an improved automatic telephone switch of the type known as a selector switch, that is one which has access to a plurality of trunk lines divided into groups and which may be numerically operated to select a desired group of trunk lines, and then operate automatically to select an idle trunk line in the group, and extend a connection thereover.

In the past a selector switch of the standard type has been given access to ten trunk lines in a level or group that is it might step ten times automatically over a level of ten trunks, and if more trunk lines were necessary, then the switch must take more than ten steps, which operation would require too great an expenditure of time.

My invention, which is in the nature of an improvement on the selector switch disclosed in the patent to Jacobsen, No. 1,352,605, granted Sept. 14, 1920, has for its object an improvement in the operation of the same together with the provision of an improved relay known as a shuntfield relay, which is adapted to perform certain functions in such a switch as will be more fully disclosed hereinafter.

Since the operation of my improved selector switch is very similar to that of the selector switch disclosed in said prior patent it will be unnecessary to describe herein the detailed operation of the circuit arrangement. I will, however, describe, fully the operation of the shuntfield relay, its functions and certain other improved features, and in a general way, the mode of circuit operation of my improved switch.

Referring now to the drawings: In Fig. 1 I have shown a calling subscriber A, having a rotary line switch C of the well known rotary type individual to his line, which is operated to select an idle one of a number of first selectors, one of which is shown at E

and which selector, is of the well known Keith, Erickson switch of the side switchless type, with the addition of certain circuits which adapt it to operate in accordance with the feature of my invention.

Referring now to Figures 2 and 3 I have shown a front and side view respectively of my improved relay. This relay is made up of two coils 1 and 2 rigidly fastened to the heel piece 6. This heel piece is merely a continuation of the frame 5 bent at right angles (Fig. 3) and constitutes part of the magnetic circuit of the relay. Pivoted at one end of the frame 5 is the armature 4 of the relay, controlling the springs 7. At the upper end of the coils 1 and 2 is a soft iron piece 3 which is fastened to the core of both magnets. It will thus be seen that this relay constitutes practically a horseshoe electromagnet having the two coils 1 and 2 with a pole piece 3 which is permanently attached. Now if either one of these coils is energized singly it is readily apparent that magnetic flux will be set up in a circuit from the core of either coil, through the heel piece 6, the core of the other coil, then through the pole piece 3, to the core of the coil energized. Consequently the coil will have no attraction whatsoever on the armature 4, which will remain in its normal position. Now if both coils 1 and 2 should be energized at the same time flux will be set up in a totally different magnetic circuit, that is of course, presupposing that the energizing current flows in the same direction in both coils, from coils 1 and 2 through the heel piece 6, the frame 5 and the armature 4. Therefore the armature 4 will pull up and shift the springs 7 into their off normal position. Having described my improved relay and its operation, I will now explain how this is incorporated in the invention disclosed in the above mentioned patent.

While in Fig. 1, I have shown a plurality of batteries it will be understood that there is but preferably one battery having its positive pole grounded.

Referring now to Fig. 1, I will describe in general the operation of my improved selector switch. When the subscriber A removes his receiver to initiate a call the rotary line switch C operates in the usual, and well known manner to select an idle trunk line leading to a selector E, and ex-

tend the subscriber's line to the line relay 25 of the selected switch. Relay 25 on energizing completes the circuit of slow acting relay 28, which on attracting its armature places ground G^1 on the release trunk 27 in the usual manner. As the subscriber operates his dial for the first digit of the desired number the line relay 25 responds to the opening and closing of his loop to operate the vertical magnet 29 in series with relay 28, which maintains its armature attracted during this series of impulses, being a slow acting relay.

Magnet 29 in operating steps the wipers 39 to 44 inclusive to some level of bank contacts from which trunk lines lead to the desired exchange or switches of any desired type. It is to be understood that wipers 40, 41 and 43 are line and private wipers of one set, having access to one bank of one hundred contacts, while wipers 39, 42, 44 are the private and line wipers of another set which have access to a separate bank of a hundred contacts, both sets of wipers being mounted on the same shaft and moving together.

At this point I will describe the operation of springs 30. These springs might be called a pair of off normal springs but they are controlled directly by the vertical and release magnets, that is as soon as the vertical magnet is energized the springs 30 make, and as soon as the release magnet is energized the springs break contact. These springs may be operated by the double dog of any Strowger switch. Springs which are operated by the double-dog of a switch are shown in the patent to Martin, No. 1,109,650, granted Sept. 1, 1914.

Returning again to the operation of the switch. Relay 28 on attracting its armature completes a circuit for both coils of relay 29. This relay is identical to the one illustrated in Figs. 2 and 3 and will therefore attract its armature and lock itself energized over a circuit extending from ground G^2 , lower armature of relays 33 and 34, conductor 31, upper make springs of relay 29, through both coils of said relay in multiple, springs 30, which are now closed, break springs 32 of rotary magnet 35 to battery. Now as soon as relay 28 deenergizes, which will take place as soon as the first series of impulses ceases, a circuit is then completed for the rotary magnet 35 extending from ground G^1 , springs 36, conductor 37, off normal springs 32, springs 38, lower make springs of relay 29, thence through the rotary magnet 35 to battery. The rotary magnet will operate to rotate the shaft carrying wipers 39 to 44 inclusive on to the first two trunk lines in the level and at the same time open the springs 32, thus opening the holding circuit of relay 29, which de-energizes. The further rotation of the

switch depends on whether or not both trunk lines are busy. Supposing this is the case, the private wipers of both sets will find ground and a circuit will be completed for both coils of relay 29, which will operate to close the rotary magnet circuit over the same circuit as previously described. This alternate operation of relay 29 and the rotary magnet 35 will continue as long as both trunks are busy. The operation of the switch when only one is busy is somewhat different. It will be readily seen that only one coil of magnet 29 will have a direct circuit for it while the other coil will have a circuit completed for itself in series with one or the other of relays 33 or 34 depending on which trunk is idle. As explained before, relay 29 is so constructed not to operate under these conditions, but the relay 33 or 34 energized in series with one of the coils of relay 29 will operate, extending the subscriber's line over the idle trunk line. Should both trunk lines be idle both relays 33 and 34 energize in series with both coils of relay 29. Relays 33 and 34 are so arranged that each opens the circuit of the other. Thus only one of them will remain energized and the subscriber's line will be extended over only one trunk line.

It has been mentioned above that as soon as the release magnet 45 of this switch operated the springs 30 were separated. Now should the wipers 39 to 44 inclusive, in releasing encounter 2 busy trunk lines simultaneously, relay 29 might again operate and interfere with the release of the switch by again completing the rotary magnet circuit, if the springs 30 were not opened when the release magnet energized.

It will therefore be seen that I have provided a very efficient type of automatic selector switch which will test 20 trucks in the same time it took previously to test 10, together with other features disclosed in the specification.

Having fully described and ascertained the features of my invention what I consider to be new and desire to have protected by the Letters Patent will be pointed out in the appended claims.

What I claim as my invention is:

1. In a telephone system, an automatic switch, trunk lines accessible thereto, a rotary magnet, a test relay for said switch, means for making certain trunk lines busy, means for operating said switch to test a pair of trunk lines simultaneously, a circuit for energizing said relay including ground-ed test contacts of busy trunk lines when said switch attempts to make connection therewith to operate said rotary magnet to cause said switch to test another pair of trunk lines simultaneously, means for releasing said switch, and means for opening said first mentioned circuit during restoration.

tion to normal to prevent any further operation of said rotary magnet in case any busy trunk line is encountered.

2. In a telephone system, trunk lines, an automatic switch accessible to said lines, testing means in said switch for locating trunk lines not in use, said testing means including two test wipers for testing said trunk lines in pairs, means for releasing

said switch, and means for rendering said testing means ineffective during the release to prevent any false operation of said switch in case the said testing means engages a busy trunk line.

Signed by me at Chicago, Cook County, 15 Illinois, this 1st day of September, 1920.

CHARLES J. ERICKSON.

tion to normal to prevent any further operation of said rotary magnet in case any busy trunk line is encountered.

2. In a telephone system, trunk lines, an automatic switch accessible to said lines, testing means in said switch for locating trunk lines not in use, said testing means including two test wipers for testing said trunk lines in pairs, means for releasing

said switch, and means for rendering said testing means ineffective during the release to prevent any false operation of said switch in case the said testing means engages a busy trunk line.

Signed by me at Chicago, Cook County, Illinois, this 1st day of September, 1920.

CHARLES J. ERICKSON.

DISCLAIMER.

1,544,300.—*Charles J. Erickson, Chicago, Ill. AUTOMATIC TELEPHONE SYSTEMS.*
Patent dated June 30, 1925. Disclaimer filed May 17, 1926, by the patentee, the assignee, *Automatic Electric Inc.*, consenting.

Hereby enters this disclaimer to claims 1 and 2 in said specification, which are in the following words, to wit:

“1. In a telephone system, an automatic switch, trunk lines accessible thereto, a rotary magnet, a test relay for said switch, means for making certain trunk lines busy, means for operating said switch to test a pair of trunk lines simultaneously, a circuit for energizing said relay including grounded test contacts of busy trunk lines when said switch attempts to make connection therewith to operate said rotary magnet to cause said switch to test another pair of trunk lines simultaneously, means for releasing said switch, and means for opening said first mentioned circuit during restoration to normal to prevent any further operation of said rotary magnet in case any busy trunk line is encountered.

“2. In a telephone system, trunk lines, an automatic switch accessible to said lines, testing means in said switch for locating trunk lines not in use, said testing means including two test wipers for testing said trunk lines in pairs, means for releasing said switch, and means for rendering said testing means ineffective during the release to prevent any false operation of said switch in case the said testing means engages a busy trunk line.”

[*Official Gazette June 8, 1926.*]

DISCLAIMER.

1,544,300.—*Charles J. Erickson, Chicago, Ill.* AUTOMATIC TELEPHONE SYSTEMS.
Patent dated June 30, 1925. Disclaimer filed May 17, 1926, by the patentee, the
assignee, *Automatic Electric Inc.*, consenting.

Hereby enters this disclaimer to claims 1 and 2 in said specification, which are in
the following words, to wit:

“1. In a telephone system, an automatic switch, trunk lines accessible thereto, a
rotary magnet, a test relay for said switch, means for making certain trunk lines
busy, means for operating said switch to test a pair of trunk lines simultaneously,
a circuit for energizing said relay including grounded test contacts of busy trunk
lines when said switch attempts to make connection therewith to operate said rotary
magnet to cause said switch to test another pair of trunk lines simultaneously,
means for releasing said switch, and means for opening said first mentioned circuit
during restoration to normal to prevent any further operation of said rotary magnet
in case any busy trunk line is encountered.

“2. In a telephone system, trunk lines, an automatic switch accessible to said
lines, testing means in said switch for locating trunk lines not in use, said testing
means including two test wipers for testing said trunk lines in pairs, means for
releasing said switch, and means for rendering said testing means ineffective during
the release to prevent any false operation of said switch in case the said testing
means engages a busy trunk line.”
